UNITED STATES PATENT OFFICE.

HENRY M. NORRIS, OF CINCINNATI, OHIO, ASSIGNOR TO THE CINCINNATI BICKFORD
TOOL COMPANY, OF CINCINNATI, OHIO, A CORPORATION OF OHIO.

CENTER-DRAIN TURNTABLE.

1,426,496.

Specification of Letters Patent. Patented Aug. 22, 1922.

Application filed April 2, 1921. Serial No. 458,091.

To all whom it may concern:

Be it known that I, HENRY M. NORRIS, a citizen of the United States, and residing at Cincinnati, in the county of Hamilton 5 and State of Ohio, have invented a new and Improved Center-Drain Turntable, of which the following specification is a full disclosure.

This invention relates to work-tables, notably for upright drills, and it deals more especially with an arrangement for disposing of either the cooling or abrading fluids used in certain machining operations; together with the small metal-chips resulting 10 from the drilling operation and which ordinarily accumulate on the table and especially in the recesses thereof. In its more restricted aspect, the invention comprehends an arrangement of channels for conducting these 15 fluid-and-chip aggregates to a common point (on, in or through the table), preferably located over and leading through one of the table-supporting members.

A type of drill-table, which admirably 20 lends itself to alteration to conform with this invention, is the conventional rotary-table having the usual radial T-slots for receiving the work-clamping bolts. In this type of table, however, the T-slots are barely 25 of sufficient depth to receive the bolt-heads, and they terminate short of any bore that may have been provided in the hub. The hub, in this type of table, is generally located at the center of the table and in most 30 cases is cast hollow to receive the drill. The present invention, through certain alterations, utilizes these characteristics of conventional tables in fulfilling a major part 35 of the requirements of a drain-system; thereby creating a work-table having a highly 40 efficient drain-system but without increasing its constructional difficulties to any appreciable extent, as compared with cost of the usual rotary-table.

In applying this invention to conventional 45 tables, the normal depth of the T-slots is increased so that, in addition to serving their normal purpose of accommodating the heads of the clamping-bolts, they will also function 50 freely as conducting-channels ample to convey the aggregates to a suitable point of deposit. In order that these collected fluids may be disposed of, the channels are arranged freely to communicate directly with the axial opening often provided in the hub 55

or, if such opening be not present, a drain-opening is especially prepared. The communication between the T-slots and the bore of the hub may be established by increasing the length of the T-slots so that, at the center of the table they open into the vertical bore, or small auxiliary channels might communicate with the T-channels and the drain-passage. The fluid, which is delivered onto the table, passes through the T-slots to a common point and is discharged into this opening in the hub. 60

Irrespective of whether the fluids are conducted to a common point by the usual T-slots or by auxiliary channels, an arrangement for disposing of the fluids collected at this point forms an important phase of the present invention. This disposition of the rather copious quantities of fluid ordinarily used in machining operations has always presented a difficult problem. In some instances, the disposal has been arranged for by drain-holes arranged at one corner in the bottom of the table; the outlet being screened to catch the chips. This custom 70 has, however, been attended with more or less inconvenience; because of the difficulty in causing the fluids to flow to this single opening, and because of an interference with the free-flow of fluid caused by a clogging 75 of the screen by the chips. The ordinary corner drain-hole is also objectionable because but two alternatives for the disposal of fluids present themselves: either the fluid is allowed to drip onto the floor or onto the 80 base of the machine (depending on the type of machine with which the table is used) or it must be conducted away by a conduit connected to the opening. Either method of 85 disposing of the fluids is inherently objectionable; the dripping-method, because of the loss of the oil and danger to the operators caused by slippery floors, and the conduit-method, because the table is prevented 90 from rotating freely and completely. 95

The present invention is therefore particularly applicable to the rotating type of drill-table; since this form of table lends itself peculiarly to the discharge of the oil at the center of the table (thereby obviating 100 either the objectionable drip or conduit connection) and also because the usual radiating T-slots of this type of table may be conveniently altered so as also to serve as channels for conducting the fluids to the center 105 110

of the table. The present invention, in its preferred form, also involves a channel encircling the table and arranged subjacent to the outer ends of the T-slots; thereby providing an arrangement for collecting the fluid-chip aggregates which spill from the portions of the table between the T-slots. Ordinarily, and in the specific embodiment of the invention shown in the drawings, these intervening portions lie in a single plane. It is to be understood, however, that the table might be cast with inclined portions between the T-slots so as to facilitate the shedding of the fluid mixtures into the encircling channel and still leave ridged portions directly adjacent to the channels to provide level radial ridges for affording the necessary level support for the work.

In the drawing, Fig. 1, is a plan view of the invention; Fig. 2 is a side elevation partly in section; Fig. 3 is a section of Fig. 1 on the line 3—3 and Fig. 4 is a section of Fig. 1 on the line 4—4.

Continuing now by way of a more detailed description, A denotes the platen or drill-table proper and B denotes the standard for supporting or positioning the table. In this instance, this standard is represented as tubular in form; it being utilized as a hub journaled in a conventional bracket (not shown) extending radially from the column of a drilling-machine in the usual manner, as will be understood. The bore of this hub, indicated by 1, extends vertically and may, if desired, open through the top of the platen so as to receive the drill and permit some of the chips therefrom to drop downwardly therethrough. In this instance, a closed platen portion 3 is located in vertical registry with the bore 1. Near its upper end, the bore 1 flares upwardly and outwardly, as indicated by 2, and is preferably enlarged to form the drain-chamber 4 which may be, between the radial ribs 11, extended radially to the annular wall 9 which provides a reinforcement and support for the horizontal wall 8 of the platen proper. A flange 14 depends from the outer margin of the platen and, adjacent this flange, is a moat 13 circumscribing or extending around near the periphery of the table; the wall 12 constituting the inner annular wall of the moat.

Channel-like ribs 11 are cast integrally with the other parts of the table and horizontally, or nearly so, extend radially through or into connection with the annular wall 9; these ribs being channeled as shown by Fig. 4 in the form of a T-slot providing an enlarged conduit 5 of materially greater depth than the head of a bolt C such as is conventionally used for clamping work to the table. The shank of this bolt is accommodated by means of the slot 6 as

will be understood. In this instance, the slot 6 terminates in an end wall 7, but the conduit 5 leads directly into the chamber 4; thereby establishing a free communication between the bore 1 and the moat 13 so that any oily aggregates, collecting either in the moat 13 or deposited through the slot 6 into the channel 5, will be washed down through the bore 1 onto the bed of the machine or into any suitable receptacle, as will be understood.

Having thus revealed this invention, I claim as new and desire to secure the following combinations of elements, or equivalents thereof, by Letters Patent of the United States:—

1. A work-table comprehending individual drain-passages having the shape of conventional T-slots and converging toward a common point; and a single downward drain-passage located at said point, said drain-passage being enlarged at its upper end to communicate with the inner ends of said drain-passages and into which they may discharge the fluids. 90

2. A work-table comprehending a series of radial drain-passages 5 converging toward a common point and a single vertical discharge passage 1 at this point with which the inner ends of said passages communicate, said drain-passages comprising narrow slots 6 for receiving the shanks of bolts and said slots 6 terminating at points 7 located concentrically to the central axis of the vertical drain passage. 95 100

3. A work-table comprehending an encircling channel and subjacent inwardly-extending radiating drain-passages communicating at their outer ends with said channel and communicating at their inner ends with a discharge opening centrally located in the table, said drain-passages being open to receive fluid throughout the greater portion of their lengths from the top surface of said table and being T-shaped to also receive work-retaining bolts. 105 110

4. A rotary work-table comprehending a hub and a platen having an encircling channel; subjacent inwardly-extending radiating drain-passages communicating at their outer ends with said channel to receive fluid therefrom and having their inner ends communicating directly with a central drain-passage provided by said hub; the radiating drain-passages being adapted to receive the heads of bolts for clamping the work. 115 120

5. A drill-table comprehending a horizontal top wall 8 having its under-side provided with an annular table-supporting wall 125 2 spaced from the top-wall to form an enclosed central drain-chamber 4; the under-side of said table being also provided with a number of channeled-ribs extending to an annular wall 9 having openings commu- 130

nimating with the channels provided by said ribs; and a tubular hub B integrally depending from said annular wall 2 and adapted to serve as a drain for said 5 chamber.

6. A drill-table comprehending a horizontal wall bordered by a moat; the under-face of said wall being integral with the funnel-like upper end of a tubular hub like 10 support; and a plurality of open conduits establishing communication between the said

moat and the funnel-like upper end of said support, said open conduits having the shape of conventional bolt-retaining T-slots.

In witness whereof, I hereunto subscribe 15 my name, as attested by the two subscribing witnesses.

H. M. NORRIS.
